UNITED STATES PATENT OFFICE

2,199,852

MOUNT MAKING MACHINE

Fred B. Iden, Cleveland Heights, Ohio, assignor
to General Electric Company, a corporation of
New York

Application November 30, 1938, Serial No. 243,192

9 Claims. (Cl. 176—3)

My invention relates to apparatus for making incandescent lamp mounts, and more particularly to apparatus for making the filament supporting structure of miniature incandescent lamps. 5 Still more particularly, my invention relates to apparatus for making a miniature lamp mount comprising a plurality of comparatively rigid lead wires joined by a glass bead having a filament supporting wire inserted therein. 10 Heretofore, miniature lamp mounts of the type described were made partly by hand, and it is an object of my invention to provide suitable apparatus for automatically making said mounts. My apparatus is of the general type disclosed in 15 Illingworth Patent 1,733,881, which issued October 29, 1929, in that it provides a turret with heads at intervals thereabout which carry the lamp parts through various stations at which the lamp making operations take place. In the apparatus comprising my invention, a glass bead is first fused to the leads of the lamp mount and then a partially formed support wire for the filament is inserted into the bead while it is still plastic. At other stations about the turret, 20 means are provided for bending the support wire to the correct relation to the leads and at the same time forming hooks in the ends of said leads to facilitate attaching a filament thereto. Other features and advantages of the apparatus 25 of my invention will be apparent from the detailed description which follows and from the accompanying drawings of a species thereof.

In the drawings, Fig. 1 is a plan view of a machine embodying my invention; Fig. 2 is a side elevation of the support wire forming and inserting apparatus thereof; Fig. 3 is a perspective view of a portion of said forming apparatus; Fig. 4 is a perspective view, on an enlarged scale, of the end of the inserting arm in operative relation to a lamp mount; Fig. 5 is an end view of the inserting apparatus; Fig. 6 is a perspective view of the hook forming and support bending apparatus; and Fig. 7 is a section through the dies of said apparatus in operative relation to the lamp mount. 45

The machine, as shown in Fig. 1, comprises a movable carrier or turret 11 having heads 10 thereon which advance the lamp parts through various stations at which the lamp making operations take place and into operative relation to other apparatus at said stations which perform said operations. This form of construction is similar to that of the apparatus disclosed in the Illingworth patent hereinbefore referred to which 50 can be incorporated with my machine to perform

the other lamp making operations not provided for thereby. For instance, the substantially rigid leads 12 and 13 of the lamp mount can be inserted automatically between the movable jaws 14 and 15 and the separator 16, which form the head 10, at station A, and the glass bead 17, which is fused to said leads 12 and 13, can be automatically threaded over the upper ends thereof at station B as disclosed in said patent. At the time of the insertion of the leads 12 and 13, the jaws 14 and 15 which are located in a circumferential channel in the turret 11 and which are pivoted on the pins 18 extending therefrom are held apart from the separator 16 by the cam 19 also disposed therebetween. Following 15 the insertion of the leads 12 and 13, the cam 19 is turned by means not shown and the jaws 14 and 15 are closed upon the separator 16 so as to grip the leads 12 and 13 located therebetween by the expanding force of the springs 20. The 20 springs 20 are located between each of the heads 10 in a position which allows them to engage the opposite jaws of adjacent heads 10 and are attached to the turret 11 by the screws 21. The glass bead 17 rests on the upper surface of the 25 jaws 14 and 15 and the separator 16 and is melted down onto the leads 12 and 13 in the regular manner by the burners 22 and 23 at stations C and D.

Upon moving from station D, the bead 17 is in 30 a fused state and a support wire 24, ultimately intended to engage and support the mid-portion of a filament attached at its ends to the leads 12 and 13, is inserted thereinto as shown in Fig. 2. The particular apparatus used for this purpose 35 depends on the type of support wire 24 required for the particular lamp being manufactured and, in this instance, is located at station E and is comprised of the apparatus 25 which partially forms said support wire 24, and the apparatus 26 40 which inserts said partially formed support wire 24. The support wire 24 is formed from the wire 27 which is wound on the spool 28 and which is threaded between the guide rolls 29, through the longitudinal groove in the slide 30 and below the 45 leaf spring 31. At the beginning of the cycle of operation, the slide 30, which is held in ways in the bracket 32, is located much lower than shown and the end of the wire 27 extending from the lower end thereof is gripped by the inserting apparatus 26 which is then in the position shown in dotted lines in Fig. 2. As the apparatus is operated, the slide 30 is moved up to the position shown and the wire 27 is pulled from the spool 28 since said spool 28 is attached to the slide 30 50 55

by the arm 33, and the end of said wire 27 is held by the inserting head 26. This movement of the slide 30 is brought about by means not shown connecting said slide 30 to the cam slide 34 in the manner of the inserting apparatus shown in Malloy Patent 2,058,332 which could be substituted for this apparatus. The slide cam 34 is held in ways in the bracket 32 which is mounted, together with the inserting head 26, on the block 35 which in turn is fastened to the standard 36 at an angle, causing the support wire 24 to be inserted into the bead 17 at the desired angle. The standard 36 can, for instance, be attached to a table which forms a part of the machine and which supports the turret 11. Movement of the slide cam 34 is brought about by the lever 37 which is connected thereto through the link 38 and which is operated by a cam (not shown) on the cam shaft 39 of the apparatus through the lever 40, the universal joints 41 and 42 and the rod 43. The lever 40 is pivoted on the pin 44 extending from the standard 36 and is turned so that a roller (not shown) on the lower end thereof engages the cam by the contracting force of the spring 45 which extends between said lever 40 and a portion of the standard 36.

Following the upward movement of the slide 30, the continuing movement of the cam slide 34 causes the heads 46 and 47 of the apparatus to advance toward and engage the end of the wire 27. The head 46 which is mounted on the lever 48 moves toward the wire 27 until the face of the die 49 and the cutting block 50, which is located between the arms 51 of the head 46, are in engagement with said wire 27. The lever 48 is pivotally mounted on the bracket 32 by the pin 52 and moves the head 46 as the roller 53 on the end thereof passes into the lower portion of the slot 54 in said slide cam 34. The movement of the head 47, which is mounted on the lever 55, first carries the forward end of the slide 56, which is held in ways therein, against the portion of the wire 27 which engages the flat portion of the die 49 so that said wire is securely held in place, and then carries the knife 57 against said wire 27 so that it is severed adjacent the cutting block 50. The movement of lever 55 occurs as the roller 58 enters the lower end of the slot 59 in the slide cam 34 and turns said lever 55 about the pin 60 by which it is pivotally attached to the bracket 32. The knife 57, as shown in Fig. 3, is attached to the head 47 between the ways provided therein for the arms 51 of the head 46 which slide therein and keep the heads 46 and 47 properly aligned.

After the slide 56 engages the wire 27, all further movement of the head 47 causes said slide 56 to move in the ways therein and expands the spring 61 which is located between the end of said slide 56 and a lug extending from said head 47. During the final portion of the movement of the head 47, the protruding die 62 thereof is carried against the now free portion of the wire 27 which forms the support wire 24 and it is bent back against the die 49 of head 46. This operation only partly forms an open hook in the end of the support wire 24 and a slide 64 in ways in the head 46 is now moved out from the head 46 to bend the remaining free portion of the end of said support wire 24 back against the transverse portion of the die 62 of the head 47 so that said hook is completely formed. The slide 64 is operated by the lever 65 which is connected thereto through the link 66 and is turned about the pin 67 extending from bracket 32 as the roller 68 on the

upper end thereof enters the lower portion of the slot 54 in the slide cam 34. The support wire forming apparatus 25 is now in the position shown in Fig. 2 and the slide cam 34 moves down until the heads 46 and 47 are separated from the support wire 27 whereupon the inserting head 26, which is then the only support for said wire 27, moves down to the position shown.

The inserting head 26 as shown in Figs. 2 and 4 engages the support wire 24 through the finger 68 which is slotted therefor and is gripped between a stationary insert 69 within a transverse slot in the end thereof and the movable block 70 also within said slot. The finger 68 is attached to the end of the rod 71 which is slidably mounted in the body 72 of the inserting head 26 and is urged forward so as to grip the support wire 24 by the spring 73 which is located in a well in said body 72 and which butts against the end of said finger 68. A corresponding movement occurs in the block 70, although in the opposite direction since the rod 71 slides in the body 72 as the finger 68 moves, and this movement is transferred through the lever 74 and the comparatively rigid wires 75 on opposite sides of the arm 68 to said block 70. The lever 74 as shown is pivotally mounted on the pin 76 carried by the body 72 and engages the pin 77 carried by the rod 71 through a slot in its end. Both the finger 68 and the body 72 of the inserting arm 68 are located between the opposite sides of the bracket 78 which keep them in proper alignment with the support wire forming apparatus 25 and the head 10 of the machine. The body 72 is pivotally attached by the pin 79 to the bracket 78 which in turn is fastened to the block 35 so as to be permanently positioned with reference to the support wire forming apparatus 25 also attached thereto.

Following the separation of the heads 46 and 47 of the support wire forming apparatus 25, the inserting arm 68 is caused to swing down until the lower end of the support wire 24 is forced into the bead 17 carried by the leading-in wires 12 and 13 in the head 10 positioned before the apparatus. This movement of the inserting arm 68 is caused by rotation of the body 72 about the pin 79 and is brought about by the cam 80 on the cam shaft 39 which is engaged by a roller on the lever 81. The lever 81 is connected to the body 72 by the link 82 and turns about the pin 83 extending from the bracket 36. The spring 84, which extends between a post in the lever 81 and a second post (not shown) in the lower portion of the bracket 36, swings the lever 81 so that the roller thereon engages the cam 80. The lower limit of movement of the inserting head 26 is reached when the finger 68 comes in contact with the roller 85 which is attached by means of the arm 86 to the bracket 78. The end of the inserting finger 68 in this instance, as shown in Fig. 4, is slotted at 87-87 to provide clearance for the ends of the support wires 12 and 13 extending upward from the bead 17.

Following the insertion of the support wire 24, the finger 68 and the block 70 are separated sufficiently to release said support wire 24 and provide clearance for the hook in the upper end thereof when the inserting finger 68 is raised and returned to its former position. The separation of the inserting finger 68 and the block 70 is brought about by the slide 88 (Fig. 2) which is moved forward until the lever 74 is engaged and turned the required amount to produce this movement. The slide 88 is mounted in ways in the lower edges of the bracket 78 (Figs. 2 and 5) in 75

which it is held by the plate 89 and is actuated by the lever 90 which is connected thereto through the link 91 and which engages the cam 92 through a roller on the pin 93. The lever 90 is pivoted on the pin 83 and is turned so that the roller thereon engages cam 92 by the spring 94 which extends between a post in said lever 90 and a second post (not shown) extending from the standard 36. The movement of lever 74 actuates the block 70 through the wires 75 and the finger 68 through the pin 71 and rod 71, the latter of which is moved until the latch 95 drops into the notch 96 therein. The latch 95 now holds the rod 71 in place so that both the inserting finger 68 and the block 70 remain separated and the slide 88 is no longer required. The inserting finger 68 is swung upward by the link 82 and other means already described, and rises until the body 72 thereof engages the pin 97, 20 which extends through the bracket 78, and the end of said inserting finger 68 and block 70 are properly positioned at opposite sides of the wire 27 protruding from the slide 30. At this time, the slide 88 is moved back so that the raised portion 88 thereof is carried below the roller 99 of the lever 100 and said lever 100 is carried upward against the end of the latch 95 lifting it from the notch 96. The lever 100 is pivotally mounted on the pin 101 and when moved stretches the spring 102 which is located between the post 103 (Fig. 5) extending through an opening in the bracket 78 allowing full movement of the lever 100 and the post 104 extending from said bracket 78. The movement of the latch 95 compresses the spring 35 73 which normally holds said latch 95 in the notch 96 or against the side of rod 71 and brings about the closing movement of the finger 68 and block 70 in the manner already described. The flange 105 on the end of the rod 71 limits the movement thereof. The following operations of the forming and inserting apparatus have already been described.

In order that the bead be sufficiently plastic to allow the insertion of the support wire 24, the fire from the burner 106 is caused to play thereupon prior to the actual insertion. As the insertion takes place, the burner 106 is turned so as not to strike the inserting finger 68 by means controlled by a fourth cam 107 (Fig. 1) on the shaft 39. The burner, as shown, is fastened to the pipe 108 pivoted in the supporting bracket 109 and turned by the lever 110, link 111 and lever 112 which engages said cam 107 through the roller 113.

All other operations of my machine take place at other stations taken by the head 10. In the instance shown, the hooked end of the support wire 24 is bent into proper relation to the leads 12 and 13 and hooks are bent into the ends of said leads 12 and 13 at station F. The apparatus for this purpose is shown in Figs. 1, 6 and 7 and comprises the dies 114 and 115, the former of which is attached to the lever 116 which is pivoted on the screw 117 extending from the standard 118, and the latter of which is attached to the lever 119 which is pivoted on the screw 120 extending from said standard 118. After the head 10 comes into position before the apparatus, the die 114 is swung into position beside the ends of the leads 12 and 13 as shown in Fig. 7 by movement of the lever 116 which is actuated by the introduction of the cam 121 on rod 122 behind the roller 123 carried by said lever 116. Normally the spring 124 which extends between posts in the lever 116 and the standard 118 holds said lever 116 and

die 114 in the retracted position. The rod 122 is supported by the standard 118 and is moved down so as to actuate the device by means not shown operated in connection with the indexing movements of the turret 11. At the same time 5 the die 114 is carried into position, die 115 is swung toward the opposite side of the leads 12 and 13 by the downward movement of the pin 125 in the biased slot 126 in the lever 119 which results from the downward movement of the arm 10 127. The arm 127 is pivoted on the pin 128 extending from the standard 118 and is carried down with the rod 122 which it engages through the screw 129 since they are joined by the spring 130 which extends between a post in each. The 15 movement of the die 115 carries the forward edge 131 thereof against the ends of the leads 12 and 13 which are bent over the teeth 132 on opposite sides of the die 114 and also carries the forward edge 133 of the bottom of the slot in die 115 20 against the support wire 24 so that it is bent over the center inserted section 134 of the die 114. Finally, the pin 125 reaches the bottom of the slot 126 in the lever 119 and the additional downward movement thereof forces the lever 119 25 downward therewith so that the leads 12 and 13 and support wire 24 are bent to the position shown. This movement carries the teeth 132 of die 114 into the correspondingly shaped notches in die 115 which bends the ends of the leads 12 30 and 13 down completing the hooks therein and carries the bottom portion 135 and the end 136 of the inserted section 134 of the die 115 more tightly against the support wire 24 which completes the bend in said support wire 24. During 35 this final movement of the lever 119, the spring 137 which extends between posts in the standard 118 and said lever 119 is stretched and the pin 120 is carried into the upper portion of the slot 138 in said lever 119. The dies 114 and 115 are 40 now separated from the leads 12 and 13 and support wire 24 which are indexed from station F. In the instance shown, the mount is not operated upon again while in the machine and is removed therefrom at station G although mechanisms for performing other operations such as the mounting of a filament and further bending of the inner and outer ends of the leads may be supplied at any of the stations of the machine. Such other operations can, for instance, be those performed by the apparatus of the Illingworth patent hereinbefore referred to.

What I claim as new and desire to secure by Letters Patent of the United States is:

1. In a machine of the character described, 55 the combination of a movable carrier having heads thereon for supporting a plurality of leads in relatively close but spaced side-by-side relation, heating means disposed adjacent the path of travel of said heads arranged to fuse a glass bead to said leads to join them together, and means also located adjacent said path of movement of the heads for inserting into said bead between said leads without disturbing their position a support wire adapted to engage a filament 60 connected to said leads.

2. In a machine of the character described, 70 the combination of a movable carrier having heads thereon for supporting a plurality of leads in relatively close but spaced side-by-side relation, heating means disposed adjacent the path of travel of said heads arranged to fuse a glass bead to said leads to join them together, means also located adjacent said path of movement of the heads for inserting into said bead between

said leads without disturbing their position a support wire adapted to engage a filament connected to said leads, a burner located adjacent said inserting means for directing a flame onto 5 the bead, and means for directing said burner away from the bead during the insertion of the support wire.

3. In a machine of the character described, the combination of a movable carrier having 10 heads thereon for supporting a plurality of leads in relatively close but spaced side-by-side relation, heating means disposed adjacent the path of travel of said heads arranged to fuse a glass bead to said leads to join them together, and 15 means also located adjacent said path of movement of the heads for severing a length of wire from a continuous length thereof, for forming a hook in one end of said length of wire and for inserting the opposite end thereof into said bead 20 between said leads without disturbing their position to provide a support for a filament adapted to be connected to said leads.

4. In a machine of the character described, the combination of a movable carrier having 25 heads thereon for supporting a plurality of leads in relatively close but spaced side-by-side relation, heating means disposed adjacent the path of travel of said heads arranged to fuse a glass bead to said leads to join them together, means 30 also located adjacent said path of movement of the heads for inserting into said bead between said leads without disturbing their position a support wire adapted to engage a filament connected to said leads, and means located at another position in the path of movement of said 35 heads for forming hooks in the ends of the leads and for bending the end of the support wire into the correct relation thereto.

5. In a machine of the character described, the combination of a movable carrier having 40 heads thereon for supporting a plurality of leads in relatively close but spaced side-by-side relation, heating means disposed adjacent the path of travel of the heads adapted to fuse a glass bead to said leads to join them together, means 45 also located adjacent said path of movement of the heads for inserting into said bead between said leads without disturbing their position a support wire adapted to engage a filament connected to said leads, and means located at another position in the path of movement of the 50 heads comprising a pair of co-acting dies, means for carrying one of said dies against portions of the leads and support wire adjacent the ends thereof and means for carrying the other die 55 against said ends of said leads and support wire and toward the other die to bend said ends of the leads and the support wire over and then against said first-mentioned die.

6. In a machine of the character described, 60 the combination of a movable carrier having heads thereon for supporting a plurality of leads in relatively close but spaced side-by-side relation, heating means disposed adjacent the path of travel of said heads arranged to fuse a glass bead to said leads to join them together, means 65 also located adjacent said path of movement of the heads for severing a length of wire from a continuous length thereof, for forming a hook in one end of said length of wire and inserting 70 the opposite end thereof into said bead between said leads without disturbing their position to provide a support for a filament adapted to be attached to the leads, a burner adjacent said

inserting means for directing a flame on said bead, means for directing said burner away from the bead during insertion of the wire therein, and means located at another position in the path of movement of the heads for bending the end of 5 the support wire into the correct relation to the leads.

7. In a device of the class described, gripping means for holding a partially formed lamp mount comprising a pair of spaced lead wires arranged 10 in approximately vertical side-by-side relation and tied together by a glass bead, support-wire forming mechanism mounted adjacent and above said gripping means and comprising a pair of opposed heads containing cooperating die members and a cutter, means for moving said heads toward each other to grip a wire therebetween and cause said cutter to sever it, and means for causing a relative movement between said die members to form a hook in the section of wire 15 held by said heads, and transfer mechanism comprising a finger member mounted to pivot in a substantially vertical plane and having means at its end for gripping said section of wire, and means operable after separation of said heads 20 to cause a pivotal movement of said finger member to transfer said wire section and embed an end thereof in the said glass bead while said 25 bead is in a plastic condition.

8. In a device of the class described, gripping 30 means for holding a partially formed lamp mount comprising a pair of spaced lead wires arranged in approximately vertical side-by-side relation and tied together by a glass bead, support-wire forming mechanism mounted adjacent and above 35 said gripping means and comprising a pair of opposed heads containing cooperating die members and a cutter, means for moving said heads toward each other to grip a wire therebetween and cause said cutter to sever it, and means for 40 causing a relative movement between said die members to form a hook in the section of wire held by said heads, and transfer mechanism comprising a finger member mounted to pivot in a substantially vertical plane and having means at its end for gripping said section of wire, and 45 means operable after separation of said heads to cause a pivotal movement of said finger member to transfer said wire section and embed an end thereof in the said glass bead between said lead wires while said bead is in a plastic condition, 50 the end of said finger being slotted to provide clearance for the said lead wires.

9. In a device of the class described, gripping 55 means for holding a partially formed lamp mount comprising a pair of spaced lead wires arranged in approximately vertical side-by-side relation and tied together by a glass bead, means for severing a section of wire from a length thereof and forming a hook on an end thereof to constitute it a support wire, means for transferring 60 said support wire toward said gripping means and embedding the end thereof opposite said hook in the said glass bead while said bead is in a plastic condition with the said support wire disposed between said lead wires and at an angle 65 to the plane defined by said lead wires, and shaping mechanism comprising die members arranged to engage said support wire and bend the hooked end thereof to bring said hook substantially into the said plane defined by said lead 70 wires.

FRED B. IDEN.
